ELECTRIC PHONOGRAPH APPARATUS

Orville M. Dunning, East Orange, N. J., assignor
to Thomas A. Edison, Incorporated, West Orange, N. J., a corporation of New Jersey

Application September 18, 1931
Serial No. 563,468

19 Claims. (Cl. 179—100.41)

This invention relates to electric phonograph apparatus for recording and reproducing sound, and more particularly to the construction of the recording and/or reproducing units employed for cutting a sound track in the record and transforming the recorded sounds into electrical currents.

While my invention is applicable to any type of phonograph apparatus, it is of particular utility when used in connection with phonographs employing a cylindrical record and more especially in phonographs of the commercial dictating machine type.

As is well known, the records used with commercial dictating machines are ordinarily shaved after using, and used again and again, whereby the thickness of the records in use may vary to a considerable extent. In addition to the variation in thickness of the record already referred to, there may be slight irregularities in the record itself or in its mounting which will tend to cause movement of the stylus as it rests upon the surface of the record during its rotation.

In recording sounds with apparatus of this type one of the difficulties is to so arrange the recording apparatus that the recording stylus makes a cut of a predetermined depth in the record. In recordings of the "hill and dale" type considerable difficulty may be met in causing the recording stylus to cut the correct depth, because of irregularities and lack of uniformity in the diameter of the record.

Another difficulty encountered is lack of quality of the recording and of subsequent reproduction due to the fact that most recording units which are suitable for use on commercial dictating machines do not properly record the high frequencies which impart clarity and definition of articulation.

In accordance with the present invention I have provided apparatus which is particularly intended to overcome the difficulties above referred to as well as others.

It is an object of this invention to provide improved apparatus for recording and reproducing on a record with minimum distortion.

It is a further object of the invention to provide a recording and reproducing unit which will record and reproduce sounds with fidelity on records varying in size, especially when used by lay operators.

It is a further object of my invention to provide apparatus of the class described which will record and reproduce speech with improved clarity and articulation.

It is still a further object of this invention to provide apparatus of the class described in which the weight effective on the stylus, and the pressure of the stylus on the record, may be controlled within wide limits.

Still other objects and advantages of my invention will be apparent from the specification.

In accordance with the preferred embodiment of my invention, I provide a novel construction of armature and mounting therefor, together with associated parts so arranged that the armature is very much shorter than those customarily employed in apparatus heretofore used, and has a very much smaller moment of inertia, providing for considerably improved recording and reproducing of the relatively higher voice frequencies which serve to impart clarity and definition of articulation to the recorded and reproduced sounds. Secondly, I so arrange these parts that the armature and its mounting are the only parts which are carried by the record and are entirely free to rotate to permit the stylus to ride upon the surface of the record and to follow irregularities thereof, without changing the flux distribution through the coils. Thirdly, I mount the armature flexibly and resiliently upon its mounting in such a way that the armature is yieldingly maintained in neutral position, as regards motions which vary the reluctance of the air gap.

By these features, which will hereinafter be described more in detail, the mass of the apparatus which is effective on the record and which must be moved thereby is made relatively small and the high frequency response is improved.

The features of novelty which I believe to be characteristic of my invention are set forth with particularly in the appended claims. My invention itself, however, both as to its fundamental principles, and as to its particular embodiments will best be understood by reference to the specification and accompanying drawings, in which like reference characters represent like elements, and in which:

Fig. 1 is a side view of one type of recorder unit embodying the invention;

Fig. 2 and 3 are end and top views, respectively, of the same unit;

Fig. 4 is a detail view of the armature suspension of the unit of Fig. 1;

Fig. 5 is a modification of the adjusting structure for the recording unit;

Fig. 6 is a side view of another form of recorder unit embodying the invention, the supporting plate and arm for such unit being omitted; and

Fig. 7 is a sectional view taken on line 7—7 of Fig. 6 but showing the supporting plate and arm. Referring particularly to Figs. 1, 2, 3 and 4, a portion of a carriage structure 5 of a common form of dictating machine is shown with a stop 6 to limit the movement of an arm 7 pivoted at 8. The arm 7 supports and carries the entire recording unit, which comprises a pair of coils 9 and 10 through which pass magnetic core members 12 and 13. The upper portion of the core members 12 and 13 are joined by a yoke 14, while the lower portions converge to form pole pieces 12a and 13a defining an air gap 16. The ends of the pole pieces 12a and 13a are cut away in cylindrical form. A magnet 18 (Fig. 3) which may be in the form of a U, has one pole abutting against an L-shaped member 19 of magnetic material which is attached to the yoke 14. The other pole of the magnet abuts a member 21 of magnetic material which connects with a U-shaped member 22. The member 22 has its extremities contacting with and suitably secured to a pair of supports 23 and 24 of magnetic material in which are threaded pivot screws 26 and 27. A yoke 30 is mounted for pivotal movement on the screws 26 and 27, this yoke having spaced projections 31 carrying a shaft 32 on which the armature 34 and parts associated therewith are mounted.

The armature 34 has a cylindrical head, which is disposed within the cylindrical air gap 16 with the axes of the air gap and of the armature head coinciding. The armature is pivoted on the shaft 32. An extension arm 34—A secured to the armature 34 is fastened at its outer end to the diaphragm 35 of a centering and restoring unit 36. The unit may be a cup-shaped device having an annular internal screw portion 37, into which the diaphragm may be fastened with a screw cover 38, and it may be provided with a washer of felt 40 or like material 39 between the screw cover 38 and the diaphragm 35 for damping the armature motion, or oil or other viscous material may be provided and confined between the diaphragm and cover. The centering unit 36 is maintained 45 in a fixed position with respect to the armature 34 by being mounted on the yoke 30 as by an arm 40, so that the centering unit 36, armature 34 and yoke 30 move as a unit about an axis through the pivot points 26 and 27. This axis 50 passes through the centre of the cylindrical armature head positioned in the gap 16 so that rotation of the armature assembly may take place without changing the flux distribution through the coils 9 and 10. The armature 34 may carry 55 at its extremity a stylus 41 which contacts with the surface of a record 42. Arm 40 may be cut away to provide an opening for the passage of arm 34—A.

The magnetic circuit may be traced from the 60 L-shaped member 19 at one pole of the magnet 18 through the magnet, through the vertical member 21, through the U-shaped member 22, dividing, and passing then along the vertical members 23 and 24, from which it passes to the 65 yoke 30, through the projections 31 to the armature 34, where the two magnetic paths unite, through the air gap 16, the two pole pieces 12a and 13a to the yoke 14, making contact with the L-shaped member 19. The yoke 30 and supports 70 23 and 24 are positioned as close together as is consistent with free rotation of the armature assembly and the same condition obtains where the armature 34 is pivoted to the yoke on the 75 projections 31. The narrower these gaps are made, the more sensitive the apparatus will be.

The coils 9 and 10 are wound and connected so that passage of current therethrough increases the flux flowing in one core branch and decreases it in the other, thereby causing the armature to swing about axis 32. In reproduction, such movement of the armature generates currents in the windings of the coils 9 and 10 by causing a shift in the flux from one core to the other. It will be noted that the two pole-pieces 12a and 13a are of the same magnetic polarity, instead of opposite, as is usually the case.

In the operation of the apparatus, it will be observed that any irregularities in the surface of the record 42 will rotate the entire armature assembly about an axis passing through adjusting screws 26 and 27 and the head of the armature. This rotation, however, does not change in any manner the position of the armature head in air gap 16 with respect to pole pieces 12a and 13a, the position of the armature head being controlled by the restoring diaphragm 35 in the unit 36. It will be understood that this centering means 36 may be replaced by springs, rubber blocks, or other like devices well known in the art.

The stylus is vibrated for recording, by variations in the flux through pole pieces 12a and 13a which attracts the head of the armature, causing it to oscillate about the axis 32. Should the armature structure exert too small or too great a pressure on the record, it may be counterbalanced about the pivots 26 and 27 by the provision of counterbalancing means similar to that employed in the recorder unit shown in Figs. 6 and 7. If desired, the restoring unit may (as in the case 110 of the apparatus shown in Fig. 5) be provided with a bracket and one or more weights may be provided to be positioned thereon, whereby weight may be added for reproducing and removed for recording.

It will be seen that the structure just described permits the stylus to swing freely up and down over irregularities in the record and permits considerable variation in the size of the records, without interfering with the operation of the 120 armature.

Referring now to Fig. 5, a modification of the apparatus is shown. The arm 45 which carries the apparatus is pivoted at 46 from the carriage 47 but in this case is provided with the arm 44 125 having an advance ball 48 which rides on the record surface 40 in advance of the cutting stylus. In this arrangement there is no stop for limiting downward movement of the arm 45, as in Fig. 1. The storing unit 36 of the apparatus shown in Fig. 5 is provided with an angular resilient bracket or arm 90 secured at one end to the unit by a screw 91, said arm being adapted to removably hold a weight 92 in position on the unit. When the apparatus is to be used for 130 reproducing, the weight 92 is applied to the unit, as shown, but when such apparatus is to be used for recording, such weight is removed. It is desirable to provide a number of different sized weights, similar to weight 92, so that when 140 the apparatus is being used for reproducing, the pressure of the stylus on the record surface may be regulated as desired by applying to the restoring unit 36 a weight 92 of proper size.

The apparatus shown in Figs. 6 and 7 illustrates the application of my invention to the usual form of magnetic circuit well known in the art, in which an armature is located in an air gap between pole pieces having opposite polarities. In this apparatus a plate 50 serves 145

- to support and hold in place the various parts of the apparatus. To the plate 50 is fastened an arm 60 which is pivoted at 61 on carriage 62 which is fed across the face of the record in any suitable manner. Stop 63 on the carriage 62 serves to limit the downward movement of the apparatus. A magnet 51 has its pole faces abutting two pole pieces 52 and 53. These pole pieces have aligned portions 52a and 53a the inner adjacent ends of which are slightly spaced and define a cylindrical air gap 55 surrounding the cylindrical head portion of an armature 56. The head portion of the armature 56 is cylindrical in cross section and the two pole pieces are concentric with this portion of the armature to permit the armature to be rotated about an axis passing through the center of the air gap without changing the flux distribution through the air gap. The pole pieces 52 and 53 are provided with adjustable pivots 64 and 65 which allow rotation of the armature support, which is a U member having arms 67. These pivot points are arranged in line with the axis of the head of the armature 56 so that rotation of the armature assembly on pivots 64 and 65 will not vary the air gap or the reluctance of the magnet circuit. The two arms 67 are of magnetic material and are provided with two bosses 68 extending therefrom in which a shaft 58 of non-magnetic material passes. This shaft also passes through an enlarged portion 56a of the armature which is free to oscillate about the axis of said shaft independently of the rotation of the armature assembly with reference to pivots 64 and 65. A coil 57 surrounds the armature and is held in place against the two pole pieces 52a and 53a. Sufficient clearance is provided in the coil to allow the armature to rotate about the axis of its cylindrical head over a considerable distance. The two arms 67 are spaced accurately and held in place by means of a bracket of non-magnetic material 70 which constitutes the base of the U member above referred to and which also is provided with an integral angular portion 72 for fastening the arms 67 to the centering and restoring unit 71. A small air gap is maintained on either side of the enlarged portion 56a of the armature 56 to prevent short circuiting of the magnet.
- 50 The remaining structure of this recorder is similar to the embodiment shown in Fig. 1, in that an arm 74 is fastened to the armature 56 at its enlarged portion 56a. This arm carries at its outer end a stylus 75 which makes contact with the record surface 76, and said arm is connected to a diaphragm 78 mounted in the unit 71. The diaphragm 78 operates in the same manner as that in the unit shown in Fig. 1, and a screw cover 80 is provided for tightening the diaphragm within the threaded portion 79. The diaphragm and associated parts constitute means for holding or restoring the armature to its central position in the air gap when it has been disturbed.
- 65 The free movement of the stylus and armature assembly without disturbing the magnetic circuit of the entire system is provided for by the pivots 64 and 65 which permit the armature assembly to rotate about a line passing through the cylindrical head portion of the armature. The armature structure may be weighted (in the manner shown in Fig. 5) or may be counterbalanced about the pivots 64 and 65. In order to so counterbalance the armature structure, one of the arms 67 of the U member referred to above, is provided with a rod 95 which extends through an opening in the plate 50 and carries a weight 96. The weight 96 is mounted on rod 95 so as to be adjustable as by being threaded thereon.
- 70 It will be noted while the armature is vibrating at sound frequencies, its vibrations are transmitted to the centering member and hence react on the armature support. In order that the armature support shall remain stationary for vibrations of sound frequency, the mass and moment of inertia of the armature is kept low with respect to that of the armature support.
- 75 While I have shown and described certain preferred embodiments of my invention, it will be understood that modifications and changes may be made without departing from the spirit and scope of my invention, as will be understood by those skilled in the art.
- 80 I claim:
1. In phonographic apparatus, in combination, a magnetic circuit, an armature disposed in a gap in said circuit for vibration therein, and a support for the armature mounted for movement about an axis passing through the armature, the armature being mounted on said support for movement about another axis passing through the armature.
- 85 2. In phonographic apparatus, in combination, a magnetic circuit, an armature disposed in a gap in said circuit for vibration therein, and a support for the armature mounted for movement about an axis passing through the armature, said armature being mounted on said support for movement about another axis parallel to said first axis and passing through the armature.
- 90 3. In phonographic apparatus, in combination, a magnetic circuit, an armature disposed in a gap in said circuit and a support for the armature mounted for movement about an axis passing through said gap, said armature being mounted on said support for vibration at sound frequencies about an axis without said gap.
- 95 4. In phonographic apparatus, in combination, a magnetic circuit, comprising spaced pole pieces providing an air gap, an armature disposed in said gap, and a support for the armature mounted for movement about an axis which is fixed with respect to said pole pieces, said armature being mounted on said support for movement about an axis spaced from and parallel to said first axis.
- 100 5. In phonographic apparatus, in combination, a magnetic circuit, an armature positioned in a gap in said circuit, and means for yieldingly supporting said armature centered in said gap for oscillation therein, said means being free to rotate about an axis central of said gap.
- 105 6. In phonographic apparatus, in combination, a magnetic circuit, an armature positioned in a gap in said circuit, a support for engaging said armature to permit vibration thereof while maintaining the position thereof, said support being mounted for swinging movement on an axis passing through the head of said armature.
- 110 7. In phonographic apparatus, in combination, a magnetic circuit, an armature positioned in a gap in said circuit, and a support for said armature, said support having said armature pivotally mounted thereon, and said support being pivotally mounted on an axis intersecting the head of said armature.
- 115 8. In phonographic apparatus, in combina-

- tion, a magnetic circuit, an armature positioned in a gap in said circuit, and a support for said armature, said support being formed of magnetic material and forming a part of said magnetic circuit, said armature being mounted for vibration on said support, and said support being mounted for swinging movement about an axis intersecting the head of said armature and parallel to the vibration axis thereof. 80
9. In phonographic apparatus, in combination, a source of magnetic potential, a magnetic circuit therefor comprising a pole piece having two branches of like polarity and having a gap therebetween, a coil associated with at least one of said branches, an armature having a head positioned in said gap, and a support of magnetic material, said armature being secured to said support for vibration, said support being mounted for swinging movement on an axis parallel to the vibration axis of said armature and passing centrally through the head of said armature, said armature and said support forming a part of said magnetic circuit and being of opposite polarity from said pole pieces. 95
10. In phonographic apparatus, in combination, a magnet, a magnetic circuit therefor comprising a pole piece having two branches and forming a cylindrical air gap therebetween, an armature having a cylindrical head portion positioned concentrically within said gap and a support on which said armature is mounted for vibration, said support being mounted for swinging movement about the axis of said armature head. 100
11. In phonographic apparatus, the combination of a magnetic circuit having a plurality of branches, and defining an air gap in said magnetic circuit, coils positioned on said branches, an armature positioned in said air gap, said armature being pivoted at a point removed from said air gap, a stylus mounted on said armature for engaging a record, and means for mounting said armature for rotation about the center of said air gap independently of the motion of said armature within said air gap. 110
12. In phonographic apparatus, a magnet, pole pieces associated with said magnet and defining a cylindrical air gap, an armature having a cylindrical head portion for operating in said air gap, said armature being pivoted at a point removed from said air gap, a stylus mounted on said armature, means for restoring said armature head to the center of said air gap when removed therefrom and means for mounting said armature assembly and restoring means for rotation about an axis passing through the center of said air gap and said armature head portion. 120
13. In phonographic apparatus, in combination, a magnetic circuit, pole pieces associated therewith and defining a cylindrical air gap, a 130
- support mounted for rotation about an axis coincident with the axis of said air gap, an armature pivotally mounted on said support for vibration and having a cylindrical head portion normally positioned concentrically in said gap, and yielding centering means mounted on said support and associated with said armature. 140
14. In phonographic apparatus, in combination, a magnetic circuit, pole pieces associated therewith and defining a cylindrical air gap, a support mounted for rotation about an axis coincident with the axis of said gap, an armature secured to said support for vibration thereon and having a cylindrical head portion normally centered in said gap, flexible and resilient centering means mounted on said support and a connection between said armature and said centering means. 150
15. In phonographic apparatus, in combination, a record, a carriage movable relatively thereto, an electromagnetic translating unit mounted on said carriage, an armature support pivotally secured to said unit for swinging movement toward and away from said record, and an armature vibratably mounted on said support. 160
16. In phonographic apparatus, in combination, a record, a carriage movable relatively thereto, an electromagnetic translating unit mounted on said carriage, an armature support pivotally secured to said unit for swinging movement toward and away from said record, an armature vibratably mounted on said support and a centering device mounted thereon in operative relation to said armature. 170
17. In phonographic apparatus, in combination, a vibratile armature, a stylus connected to said armature for engaging a record, a swingable support for said armature movable toward and away from said record about an axis intersecting said armature, and means for controlling the pressure of said stylus on said record. 180
18. In phonographic apparatus, in combination, a vibratile armature, a stylus connected to said armature for engaging a record, and a swingable support for said armature movable toward and away from said record about an axis intersecting said armature, the mass of said armature being small with respect to the mass of said armature support. 190
19. In phonographic apparatus, in combination, a vibratile armature, a stylus connected to said armature for engaging a record, a swingable support for said armature movable toward and away from said record about an axis intersecting said armature, the moment of inertia of said armature being small with respect to that of the armature support. 200

ORVILLE M. DUNNING. 135
